VARIABLE CONDENSER

Filed June 23, 1924

UNITED STATES PATENT OFFICE.

HARRY H. IDE, OF LA GRANGE, ILLINOIS, ASSIGNOR TO KELLOGG SWITCHBOARD AND SUPPLY COMPANY, OF CHICAGO, ILLINOIS, A CORPORATION OF ILLINOIS.

VARIABLE CONDENSER.

Application filed June 23, 1924. Serial No. 721,627.

My invention relates to condensers and has to do more particularly with variable condensers with an air dielectric, such as are now in general use in radio or wireless sets, and 5 an object of my invention is the provision of an improved condenser of the variable type, which is provided with structural features which will facilitate assembly of a condenser of this type and, at the same time, provide an 10 improved condenser structure which will permit the efficient operation of the same and be of the low loss type.

The condenser of my invention is of the type in which the rotary plate element is eccentrically located in relation to the semi-circular fixed plates, so that the capacity of the condenser may be made to vary in the desired manner, which of course, is well understood by those skilled in the art. 15 One of the features of my invention is the provision of simple means for supporting the rotor element and stator or fixed element of my condenser in operative position relative to each other. 20 Another feature of my invention is the provision of simple means for giving a vernier adjustment to the rotor element of my condenser relative to the fixed or stator element so that a very fine adjustment of the same 25 may be effected to obtain an efficient operation of my condenser.

Still a further feature of my invention is the provision of simple and dependable frictional means for maintaining the rotor element in its adjusted position relative to the fixed or stator element of my condenser.

Another feature of my invention is the means provided and the manner in which I space and secure the plates of the rotor element together to form a single mountable unit, and also the plates of the fixed or stator element of my condenser to form another single unit.

A further feature is the provision of means 45 for adjusting the plates of the rotor element and the plates of the stator element of my invention relative to each other without disassembling any part of my condenser.

The above features, as well as others, will 50 be more clearly and specifically pointed out in the ensuing specification and appended claims, and for a clearer understanding of the same reference may be had to the accompanying drawing.

Referring to the drawing: 55
Fig. 1 is a view in elevation of the condenser of my invention;

Fig. 2 is a right side view of Fig. 1 with the dial and vernier button removed;

Fig. 3 is a bottom plan view of Fig. 1 and 60 showing certain parts thereof cut away to show other parts of my condenser;

Fig. 4 is a sectional view along the line 4—4 of Fig. 2 and also showing in section a part 65 of the vernier adjusting means of my condenser;

Fig. 5 is a plan view of Fig. 1;

Fig. 6 is a perspective view of one of the spacing members of my invention for spacing the plates of the rotor and stator elements of 70 my condenser;

Fig. 7 is a partial view of my condenser showing the stop means for limiting the amount of rotation of the rotor element.

Referring now in detail to my invention 75 as illustrated in the drawing R is the rotor element while S is the fixed or stator element of my condenser. The rotor element R comprises a plurality of substantially semi-circular plates 1 of some suitable conducting 80 material, each plate 1 having a semi-circular portion 2 formed integrally with the straight edge of said plate and provided with a suitable opening through which the rotatable shaft 3 extends. The plates 1, which form 85 the end plates of the rotor element R, each have a ring member 4 soldered to its body portion 2, each of said ring members having a suitable central opening which is adapted to align with the opening in the portion 2 of its 90 associated end plate 1. In assembling the plates 1 of the rotor element R the same will be placed in a suitable fixture provided for assembling purposes, so that the plates to which are soldered the ring members 4 will 95 be one at each end. Right angularly shaped members 5 are provided, each of which is provided with a plurality of slots 6, corresponding in number to the number of plates 1 of the rotor element. A spacing member 5 is positioned in the angle 7, formed by the plate 1 and its body portion 2, so that a portion 8 of the plates 1 will protrude through openings or slots 6 provided in the spacing member 5.

When the plates 1 are engaging the slots 6 105 in the spacing member 5 as just pointed out, solder will be applied to the protruding portions 8 whereby the plates 1 are soldered to

the spacing member 5. The slots 6 are uniformly spaced apart, and as there is only one plate 1 engaging a slot 6, it will be at once seen that the plates 1 are separated from each other and secured individually to the spacing member 5. Another spacing member 5 will be placed in the opposite angle corresponding to that of angle 7 in the same manner as just described. Thus it will be seen that the plates 1 of the rotor element R are secured in the slots 6 of a pair of spacing members 5 to form a single unit and that said plates are separated and uniformly spaced from each other by said pair of spacing members 5.

Referring now to the fixed or stator element S of my condenser, the same comprises a plurality of semi-circular plates 10, formed of suitable conducting material, and each having a portion of its body cut away to form an arcuate shaped recess 11 for purposes to be pointed out later. Spacing members 12 and 12' having their one edge 13 turned over substantially at right angles to the main body portion thereof are provided. Each member 12 and 12' is provided with a plurality of slots 14 in the turned over edge 13, corresponding in number to the number of plates 10. In assembling the plates 10 of the stator element S, the same are placed in a suitable fixture provided for assembling the plates 10 of said stator element S. When the plates 10 are placed into the assembling fixture the spacing members 12 and 12' are positioned on the plates 10 as shown in Figs. 2 and 3 so that one of the plates 10 will engage one slot 14 in each of the spacing members 12 and 12', the slot 14 being deep enough to permit a portion 15 of the plate 10 to extend below the turned over edge 13. Solder is now applied to the extending portions 15 of the plates 10 whereby the said plates 10 are soldered to the spacing members 12 and 12'. A pair of spacing members 5', similar in construction to spacing members 5 of the rotor element R, are also provided for the stator element S. The corners 16 of the plates 10 are adapted to extend through the slots provided in the spacing members 5' whereupon solder is applied to the protruding corners 16 to secure the plates 10 in the slots of the said spacing members 5'. Thus it is apparent that the plates 10 of the stator element are secured in the slots of the spacing members 5' and members 12 and 12' to form a single unit, and are separated and uniformly spaced from each other by said spacing members.

Having described the construction and manner of assemblage of the rotor and stator elements of my condenser, I will now describe how the same are supported in operative relation to each other.

A U-shaped supporting member 18 having an inwardly extending web member 19 integrally formed therewith, is provided. The

stator element S is disposed between the legs 20 and 21 of the U-shaped member 18 and is secured and supported in position by means of a pair of insulation strips 22 and 23 which are separated by and secured to the web member 19 by screws 24 which extend through suitable openings in the said strips 22 and 23 and have screw-threaded engagement with suitably tapped orifices in the said web member 19. The spacing members 12 and 12' of the stator element S engage the insulation strips 22 and 23 respectively and are secured to said strips by means of suitable bolts or screws 25 and 25' which are secured in said strips 22 and 23 respectively and extend through suitable openings in the spacing members 12 and 12' respectively and have screw threaded engagement with suitably tapped nuts 26 and 26'. The openings in the insulating strips 22 and 23 are slightly larger than the diameter of the screws 24 for purposes to be pointed out later.

In a suitable opening in the free end of the leg 20 of the U-shaped member 18 is secured a cylindrical member 29 provided with a circumferential flange 30, integrally formed therewith, said member 29 extending through a suitable opening in the said leg 20 so that the flange 30 engages the inner face of said leg, and to secure the said member 29 in position a nut 31 is provided which has screw threaded engagement with the member 29 and is adapted to engage the outer face of the leg 20. One end of the central opening in the cylindrical member 29 is enlarged and cone shaped for purposes to be subsequently pointed out. In a suitable opening in the free end of the leg 21 of the U-shaped member 18 is secured a cylindrical member 33, which member 33 is provided with a circumferential flange 34 integrally formed therewith and adapted to engage the inner face of the leg 21, by means of a nut 35 which has screw threaded engagement with the said member 33 and is adapted to engage the outer face of the leg 21. One end of the central opening in the member 33 is enlarged and cone shaped for purposes to be hereinafter pointed out.

The rotor element R is now placed so that the plates 1 engage the air spaces between the plates 10 of the fixed or stator element S. The rotatable shaft 3 is now inserted through the central opening in the member 29, and through a cylindrical member 37, and then through the aligned openings in the ring members 4 and plates 1 of the rotor element R, through the opening in the cylindrical member 38, and opening in the cylindrical member 33. The members 37 and 38 are slideable on the shaft 3 and the shaft 3 is rotatably supported in the cylindrical members 29 and 33. When the shaft 3 is positioned as just described above, the member 37 has its cone shaped end fitted into the cone shaped portion of the opening in the cylindrical member 29

and a set screw 40 is provided which extends through a threaded orifice in the said member 37 and is rotated inwardly to make frictional engagement with the shaft 3. Likewise the member 38 has its cone-shaped end fitted into the cone-shaped portion of the central opening of a member 33 and a set screw 41 is provided which has screw-threaded engagement with a tapped orifice in the said member 38 and is rotated inwardly to make frictional engagement with the shaft 3. The members 37 and 38 are secured to the shaft 3 against rotary movement relative thereto by the set screws 40 and 41 respectively and the said members engaging the cylindrical members 29 and 33 respectively will prevent endwise movement of said shaft 3. The members 29 and 33 and the members 37 and 38 serve as bearings for the shaft 3 as is obvious from the drawings. The plates 1 of the rotor element R are now adjusted between and relative to the plates 10 of the stator element S by sliding the rotor plate unit on the shaft 3 and when the desired adjustment is obtained, set screws 44 extending through suitably tapped orifices in the ring members 4 are rotated to move the same inwardly to make frictional engagement with the shaft 3 whereby the rotary plate unit is secured on the shaft 3 against rotation and longitudinal movement thereon, and in its adjusted position relative to the stator element S. The plates of the stator element S may be adjusted as a unit relative to the plates of the rotor element R by loosening a certain one or all of the screws 24 depending on the desired adjustment, which will permit a small amount of movement of the insulating strip or strips supporting the stator element S at the point where the screw 24 is loosened and when the stator element is adjusted as desired the loosened screw or screws 24 are again tightened to hold the strips 22 and 23 respectively in their adjusted place. A terminal member 24' for receiving an external conductor is secured on the screw 25' and in engagement with the spacing member 12' by the nut 26'.

A washer 46 fits loosely over the protruding end of the shaft 3 and is adapted to engage the end of the member 33 and the face of the nut 35. The protruding end of the shaft 3 is reduced at 47 and is adapted to fit into a washer 48 which is held on the said reduced end by a screw 49 which engages a tapped orifice in the end of said shaft 3, and a lock nut 50. A pig tail or a ribbon 51 of conducting material has its one end soldered to the shaft 3 and then is wound around the shaft 3 between the washers 46 and 48 and has its other end soldered to a conducting terminal 52 secured to the leg 21 of the U-shaped frame 18 by the screw 53. The conducting member 51 connects the rotor element R in circuit with the U-shaped frame 18 for the well known purposes. The loose fitting wash-

er 46 serves to prevent the conducting member 51 from catching on the rough edges of the member 33 and nut 35 when the shaft 3 is rotated.

The member 38 has a flange 54 integrally formed therewith which extends approximately half way around the said member 38, said flange adapted to have its ends 55 and 55' engage the right angular end 19' of the web member 19 of the U-shaped frame 18 to limit the degree of rotation of the rotor element R to approximately 180 degrees, which will permit the plates 1 of the rotor element R to rest entirely between the plates 10 of the stator element S, or to clear the plates 1 of the said stator element S. The arcuate recesses 11 provided in the plates 10 of the stator element S permit rotation of the rotor element R.

To rotatably adjust the rotor element R relative to the stator element S of my condenser and to hold the same in its adjusted position, I provide an arm member 57 which has its one end 58 bifurcated for receiving an eccentric member, and its other end formed to provide an adjustable clamping member 59. The adjustable clamping member 59 is adapted to fit over the end of the cylindrical member 29, and interposed between the said member 29 and said clamping member 59 is a split ring member 60 of fiber or some other suitable material. A screw 61 is provided which extends through an opening in one of the extending ends of the clamping member 59 and has screw threaded engagement with a suitably tapped orifice in the other extending end of said clamping member 59. The member 59 is so formed that its extending ends are slightly separated from each other and when the adjustable screw 61 is rotated in a certain direction the said ends are drawn toward one another to clamp the arm 57 and fiber ring 60 in position on the cylindrical member 29 but not so tight that the said arm 57 and ring member 60 cannot rotate relative to said member 29, the members forming the clamping members 59 are flexible enough to permit this adjustment. By rotating the adjustable screw 61 any degree of frictional engagement may be obtained between the ring member 60 and the cylindrical member 29.

A dial D of suitable insulating material is provided and has a central opening for receiving the free end of the shaft 3 and when in position on said shaft a set screw extending through said dial is rotated and brought into frictional engagement with the shaft 3 to prevent rotation of said dial D on the shaft 3 so that when the dial is rotated the shaft 3 will operate to rotate the rotor element R relative to the stator element S. Near the circumferential edge of the dial D is a screw threaded member 63 which extends through a suitable opening in a bearing member 64 secured in the dial D, and has screw threaded engagement with a suitably tapped opening 130

in an insulating button or member 65, the other end of the member 63 being formed to provide a flat head 66 for said member 63 which will prevent the displacement of said member 63 from the dial D. Integrally formed with the head 66 of the member 63 and eccentric relative thereto is an eccentric member 67 circular in shape and extending outwardly from the head 66, said eccentric member 67 adapted to engage and rest in the slot provided in the bifurcated end 58 of the arm 57 when the dial D is secured on the shaft 3.

Having described the construction of the condenser of my invention, I will now describe the operation of the same in adjusting the rotor element R relative to the stator element S.

To adjust the plates 1 of the rotor element R relative to the plates 10 of the fixed or stator element S, and assuming that the rotor element is in the position shown in Figs. 1 and 2, the dial D may be grasped by the operator and turned in a clockwise direction whereby the rotor element R will be rotated to adjust the same relative to the stator element S. When the dial D is rotating the arm 57 and ring member 60 will also rotate around the cylindrical member 29, in the same direction with the dial D, since the eccentric member 67 engages the bifurcated end 58 of the arm 57 and also due to the fact that the clamping member 59 and ring member 60 are not clamped too tight on the said member 29 so that they are prevented from rotating thereon when the dial D is rotated. The ring fiber member 60 has such frictional engagement with the cylindrical member 29 that when the dial D is brought to rest the arm 57 will remain in this position and the said dial D and shaft 3 will be held in the position rotated to whereby the rotor element R will be held in its rotatably adjusted position. Now to obtain a finer adjustment of the rotor element R relative to the stator element S, the operator will rotate the button or insulating member 65 in a clockwise or counter clockwise direction which will cause the eccentric member 67 to move within the bifurcated end 58 of the arm 57, and due to the fact that the said member 67 is eccentrically located relative to the head 66 of the rotatable member 63 and also engages the slot in the bifurcated end 58 of the arm 57, the dial D will be rotated one degree or less depending on the amount of rotation of the button 65, which degree of rotation will be imparted to the rotor element R to rotate the same a like degree relative to the stator element S. The eccentric member 67 and the bifurcated end 58 of the arm 57 are arranged so that by operating the button 65 the rotor element R may be rotated one degree or less than one degree. When the button 65 is operated the arm member 57 does not move due to the frictional engagement of the ring

fiber member 60 and the cylindrical member 29, and after the rotor element R is adjusted relative to the stator element S by the button 65, the same is maintained in this position by the frictional means, and the engagement of the eccentric member 67 in the slot of the bifurcated end 58 of the arm 57 as hereinabove described.

By having the frictional means arranged as described above for maintaining the rotor element R in its rotatably adjusted position instead of having the members 37 and 38 frictionally engaging the members 29 and 33 respectively for holding said rotor element R in its adjusted position a better and smoother adjustment is afforded, for it has been experienced that certain irregularities appear between the faces of the members 29 and 37 and between the faces of the members 33 and 38 and which irregularities will not permit a very smooth movement of the rotor element R but by my frictional means a very smooth operation of the rotor element R is effected.

My condenser may be mounted on a suitable mounting panel, such as that shown in dotted lines in Fig. 1, by means of suitable screws which will pass through suitable openings in the mounting panel and then have screw-threaded engagement with suitable tapped orifices in the lugs 70 and 71 integrally formed with the leg 20 of the U-shaped frame 18. The screws may be tightened as much as possible without causing the shaft 3 to bind in the legs 20 and 21.

From the foregoing description and from the drawings it will be at once apparent that I have produced a condenser which is provided with simple means for adjusting the rotor and stator elements without disassembling my condenser; that simple means are provided for supporting and spacing the plates of the rotor element and of the stator element; that simple adjustable means are provided for adjusting the rotor element on the rotatable shaft, and that adjustable means are provided for adjusting the rotatable shaft in the U-shaped supporting frame; that simple and dependable as well as adjustable frictional means are provided for maintaining the rotor element in its rotatably adjustable position; that simple means are provided for effecting a vernier adjustment of the rotor element relative to the stator element; and that other features and advantages are present in my invention which combine to make my condenser a very simple, durable and inexpensive one to manufacture and whose operation is very efficient.

While I have described and illustrated a particular embodiment of my invention, it is to be understood that I do not wish to be limited to the exact structure as shown and described, as many changes and modifications will readily suggest themselves, therefore, it is to be understood that I intend to cover all

that which may come within the scope and spirit of the appended claims.

Having described my invention what I claim as new and desire to secure by Letters 5 Patent is:—

1. A device of the class described including a fixed element comprising a plurality of conducting members, L shaped supporting members having a plurality of slots adapted to receive said conducting members, whereby said conducting members are supported and uniformly separated from each other by said L shaped supporting members and secured thereto to form a single mountable unit, a 10 U-shaped supporting frame, and adjustable means for adjustably supporting said unit on said supporting frame.
2. A device of the class described including a plurality of conducting plates, L-shaped 15 conducting members provided with openings and adapted to receive said conducting plates to support and uniformly space said plates from each other, means for permanently securing said plates to said L-shaped conducting members to form a single mountable unit, non-conducting members secured to a pair of said L-shaped conducting members, a supporting frame, a rotor element rotatably supported in said frame, and means for adjustably supporting said single mountable unit on said supporting frame in operative relation to said rotor element.
3. A device of the class described including a supporting frame, a rotor element having a plurality of uniformly spaced plates, a stationary element having a plurality of uniformly spaced plates, individual means for each of said elements for rotatably supporting said rotor element and securing said 25 stationary element on said supporting frame, and individual adjusting means for each of said elements so that the plates of one may be adjusted relative to the plates of the other of said elements.
4. A device of the class described including a U-shaped supporting member, a rotor element having a plurality of conducting members, a rotatable shaft for rotatably supporting said rotor element between the legs of said U-shaped supporting member, a stationary element having a plurality of conducting members, means for adjustably supporting said stationary element between the legs of said U-shaped supporting member, and means for adjusting said rotor element on said rotatable shaft so that the plates of said rotor element are operatively disposed relative to the plates of said stationary element.
5. A device of the class described including a U-shaped mounting member, a fixed element disposed between the legs of said mounting member, means for supporting said fixed element on said mounting frame, a rotor 60 element, a rotatable shaft for said rotor element, bearing members secured in the legs of said mounting member for supporting said shaft, adjustable means for adjusting said shaft and adapted to engage said bearing for holding said shaft in its adjustable position, and means for adjusting said rotor element on said shaft and also relative to said stationary element.
6. A device of the class described including a mounting frame, a plate element supported on said frame in a fixed position, a rotor plate element, a rotatable shaft for said second element, means for rotatably supporting said shaft in said frame, means for adjusting said shaft and rotor plate element relative to said first plate element, and means for adjusting said rotor plate element on said shaft relative to said first plate element without adjusting said shaft.
7. A device of the class described including a mounting frame, cylindrical members secured in said frame, a rotor element, a shaft, positioned in said cylindrical members for supporting said rotor element, a dial secured to said shaft for rotating the same, adjustable frictional means encompassing one of said cylindrical members, and an arm integral with said frictional means to operatively connect said dial with said adjustable frictional means for holding said shaft and rotor element in any of the rotatable positions, and a member secured to said shaft and a flange integrally formed with said member adapted to engage said frame to limit the amount of rotation of said shaft and rotor element.
8. A device of the class described including a mounting frame provided with openings and having tube members secured in and extending through said openings, a fixed element supported by said mounting frame, a shaft rotatably supported in said tube members, a dial for said shaft for rotating the same, a rotor element secured to said shaft, a non-conducting member secured to said shaft and adapted to rotate said shaft to rotatably adjust said rotor element relative to said fixed element, a non-conducting member having frictional engagement with one of said tube members, adjustable clamping means for clamping said non-conducting member on said one tube member, an arm integrally formed with said clamping means and having its one end provided with a slot, a rotatable member rotatably supported in said dial, an eccentric member for said last member adapted to engage said slot in said arm, said eccentric member when rotated adapted to effect a vernier adjustment of said rotor element through the medium of said dial and shaft.
9. A device of the class described including a mounting frame, a fixed element and supporting means for securing said fixed element

- to said frame, cylindrical members secured in and extending through openings in said frame, a rotatable shaft rotatably supported in said cylindrical members, a rotor element secured against rotation on said shaft and in operative relation with said fixed element, means for adjusting said rotor element on said shaft and also relative to said fixed element, frictional means for one of said cylindrical members, means for adjusting said frictional means, said last means having an arm member provided with an opening, a dial for said shaft for rotating the same, an eccentric member rotatably supported by said dial and adapted to engage the opening in said arm member, said eccentric member operable to effect an infinitesimally rotatable movement of said dial and said rotor element, while said arm member remains inert.
- 10 10. A device of the class described including a mounting frame, a shaft rotatably supported by said frame, a rotor element secured on said shaft against rotation, means for adjusting said rotor element on said shaft, a dial member for rotating said shaft and rotor element, means for holding said shaft and rotor element in its rotatably adjusted position, and other means including an eccentric member operatively connected with said first
- 15 20 25 30 35 40 45 50 55
- fecting a vernier adjustment of said dial and shaft.
11. A device of the class described including a mounting frame, bearing members supported by said frame, a shaft rotatably supported in said bearing members, a pair of cylindrical members adapted to maintain said shaft in position, a dial secured to said shaft for rotating said shaft, and a flange formed integrally with one of said cylindrical members adapted to engage said frame to limit the amount of rotation of said shaft and said dial, means for frictionally engaging one of said bearing members, adjustable means for adjusting the frictional engagement of said frictional means and said one bearing member, a member integrally formed with said adjustable means and provided with an opening, an eccentric member for engaging said opening, means for rotatably supporting said eccentric member, and means for rotating said eccentric member to effect a limited movement of said extending member to cause vernier movement of said dial and shaft.

Signed by me at Chicago, in the county of Cook, State of Illinois, this 21st day of June, 1924.

HARRY H. IDE.
